CLAIM

I claim the ornamental design for a wheel cover and rim shield with multi-ridged grip, as shown and described.

DESCRIPTION

FIG. 1 is a perspective view of a wheel cover and rim shield with multi-ridged grip showing my new design;

FIG. 2 is top plan view thereof, the bottom plan view, the left side elevational view and the right side elevational view being identical thereto;

FIG. 3 is a front elevational view thereof;

FIG. 4 is a rear elevational view thereof; and

FIG. 5 is a reduced perspective view showing the wheel cover and rim shield with multi-ridged grip in use; the broken lines depict environmental structure and form no part of the claimed design.
